CARD PERFORATING MACHINE

Roff Elliott, Watertown, Mass.

Application June 8, 1936, Serial No. 84,149

26 Claims. (Cl. 164—111)

This invention relates to a machine for punching perforations in cards, such as address bearing stencils and printing plates, employed in addressing machines in the manner described in the copending applications of Harmon P. Elliott, Serial No. 69,803, filed March 20, 1936, and Serial No. 75,118, filed April 18, 1936.

Such addressing machines are arranged to record on a record sheet, usually concurrently with the recording of an address, selected items of statistical information denoted by the relative position of marks formed on the record sheet under control of perforations located in selected differently positioned zones of the address bearing stencil or printing device. The stencil or printing device is provided with a plurality of differently positioned zones, each zone representing a different item of statistical information and adapted to have a perforation when such item is to be indicated on the record sheet.

One of the objects of the present invention is an improved machine for selectively perforating the cards, as the stencils or other printing devices, for this purpose.

In a copending concurrently filed application of Harmon P. Elliott, Serial No. 84,150, a card perforating machine is disclosed utilizing a plurality of punches selectively caused to be operated at the will of the operative to form the perforations in desired zones of the card. It is an object of the present invention to provide a card perforating machine wherein but one punch is employed, the punch being movable into register with zones of the card selected at will by the operative and caused to be operated to form a perforation in the card when located in any selected position.

A further object of the invention is the provision of a reciprocating punch operating plate that confronts the perforating receiving zone of the stencil and has an area approximately coextensive with the area of such zone and a punch interposed between said plate and the card or stencil and capable of being located in any selected zone of the card and operated by the plate.

Another object of the invention is the provision of a card perforating machine having a single movable punch and an index plate divided into zones corresponding in number and position to the perforation receiving zones of the stencil, and means so arranged that when a pointer is positioned at a selected zone of the index plate the punch will be disposed in register with the

corresponding zone of the card whereby to effect the perforating of such selected zone.

Another object of the invention is a card perforating machine comprising an index plate having zones corresponding in position and number to the perforation receiving zones of the card, punching mechanism including a pointer movable into register with a selected zone of the plate for positioning a punch in register with the corresponding zone of the card, and means controlled by the pointer for effecting a punching operation of the mechanism.

A yet further object of the invention is the provision of a card perforating machine having a perforating device and indexing means controlling both the position of the perforating device with respect to the card to be perforated, and the operation of said device.

Another object is generally to improve the construction and operation of card perforating machines.

Fig. 1 is a front elevation of the perforating machine embodying the present invention.

Fig. 2 is a cross sectional detail of the machine taken along line 2—2 of Fig. 1.

Fig. 3 is a plan view of the middle portion of the machine and illustrating particularly the index plate and the punch positioning mechanism.

Fig. 4 is a sectional detail of the operating mechanism for the punch reciprocating member taken along line 4—4 of Fig. 2.

Fig. 5 is a sectional elevation of the perforation selecting pointer.

Fig. 6 is a detail of the supporting bearing for the pantograph linkage connecting the pointer and punch, taken along line 6—6 of Fig. 3.

As illustrated in Fig. 3, the card or printing device comprises a stencil 16 having in one portion a stencil sheet 18 bearing an address 20, and in another portion a series of zones 22, the different positions of which denote different statistical items. The zones 22 are arranged in horizontal and vertical columns and are consecutively numbered as at 24.

The stencil herein shown has provision for one hundred and five (105) zones although the precise number is of no particular importance to the present invention. Each zone is preferably provided with a mark as a small circle 26 printed thereon for indicating the location of a possible perforation. When the stencil is perforated by the machine of the present invention such marks 26 are not necessary. They are desirable, however, for indicating the location of a perforation that may be formed subsequently by hand.

The stencil is adapted to receive perforations 28 in selected zones. The perforations control the passage of marking members through the stencil and into pressure applying relation with 5 a record sheet thereunder for the purpose of making a mark on the record sheet in a location corresponding to the location of a perforation. The marks thereby indicate by their position on the record sheet the items of information denoted by the perforated zones of the stencil.

The machine for perforating the stencil comprises a table 30, see Figs. 1, 2 and 3, supported on uprights 32 and having its operative parts operated by a power device 34, now common in 15 the art. The power device includes a continuously rotating shaft 36 and an intermittently rotating shaft 38, the latter shaft being arranged to make one complete revolution per operation and then to stop. The rotation is under control 20 of a pedal 40, which when depressed and subsequently released effects one complete rotation of the shaft 38.

A collection of the stencils 16 preferably with the addresses 20 thereon is contained in a holder 25 42 disposed at one end of the table 30 and in register with the entrance of a stencil track formed by a pair of horizontally spaced guide rails 44 which are spaced above the table. The successive lowermost stencils of the holder are advanced 30 in successive order into and along the track by a reciprocating pusher 46. Said pusher is reciprocated by a vertical lever 48 pivoted to the frame of the machine at 50 and connected to the pusher by a link 52. The lever is reciprocated by means 35 including an eccentric 54 which is fixed to and is rotatable with the shaft 38. The eccentric has an eccentric strap 56 that is swiveled to the end of a pivoted arm 58 that reciprocates a lever 60 bearing against the lever 48 and connected thereto 40 through a tension spring 62. The arrangement of the arm 58, lever 60 and spring 62 is such as to permit reciprocation of the parts as a unit under ordinary conditions but to permit the lever to stop reciprocation if a stencil or printing device should jam in the track 44. The perforated stencils are discharged from the end of the track 45 into a stencil receiver 64.

The successive stencils rest momentarily stationary in the middle portion of the track where 50 they are operated upon by the punching or perforating mechanism. Said mechanism includes a bracket 66 fixed to and upstanding above the table 30 alongside and in the rear of the stencil track. Said bracket is provided with a pair of 55 parallel bosses 68 in which a pair of vertical rods 70 are reciprocable. A punch operating member 72 is fixed to the upper ends of the rods 70 by means including nuts 74 and reciprocates with the rods. Said member 72 is in the form of a 60 flat plate which is positioned above and overlies substantially completely the entire perforation receiving zones of the stencil.

The lower ends of the rods below the table are 65 connected by a plate 78. The rods are reciprocated by toggle mechanism which includes a bracket 80 fixed to said plate 78 between the rods. A pair of toggle links 82 are pivoted at 84 to said bracket and have their upper ends disposed between and pivotally connected at 86 with the 70 short arm 88 of a bell crank lever. Said bell crank lever is pivoted on a shaft 90 carried by a bracket 92 fixed to the under side of the table 75. The long arm 94 of said bell crank lever extends rearwardly of the machine and is pivotally connected to the upper end of a rod 96. The

lower end of the rod is connected to an eccentric strap 98 operating on an eccentric 100 journalled loosely on a shaft 102. Said shaft is rotatably supported in bearings 104, see especially Fig. 1, and is continuously rotated from the continuously rotating shaft 36 of the power mechanism by means of pulleys 106, 108, and the belt 110.

The eccentric 100 is adapted to be connected with the shaft 102 for rotation therewith by means of a ratchet 112 fixed to the shaft on one side of said eccentric. A collar 114 fixed to said shaft on the other side of said eccentric serves to hold said eccentric from axial displacement. Said ratchet 112 is provided with a series of teeth 116, four teeth being here shown. Said teeth are 15 adapted to engage a pawl 118 fixed to a shaft 120 pivoted in and extended through the eccentric. Said shaft has an arm 122 fixed thereto on the other side of the eccentric which is engaged by a tension spring 124 that continually biases 20 said pawl for movement towards the ratchet. When the pawl is engaged with a tooth of the ratchet the ratchet and eccentric are rotated conjointly. When, however, the pawl is disengaged from a ratchet tooth the eccentric remains 25 stationary with the eccentric at the top of its stroke. The reciprocation of the eccentric serves to straighten and collapse the operating toggle consisting of the links 82 and the short bell crank arm 88 and thereby reciprocates the punch operating plate 72 toward and away from the stencils.

The engagement of the pawl 118 with and its disengagement from the ratchet 112 is effected by means of an electromagnet 126 carried by the plate 78 and having an armature or core 128 movable into and out of the magnet. Said core is connected to and reciprocates a slide bar 130 which slides in a bracket 132 fixed in the under side of said plate 78 and has its rear end disposed in the path of rotation of the latch 118. A tension spring 134 is connected with said slide bar 130 and serves normally to maintain the slide bar and the armature in a retracted position.

In this position the rear end of the slide bar can be engaged by the latch 118 as it rotates. 45 The operation is such that the rotation of the eccentric disc 100 with the latch in engagement with the slide bar, and also the upward movement of the bar, causes the withdrawal of the latch from engagement with a ratchet tooth, thereby 50 freeing the eccentric from the continuously rotating shaft 102 and holding the eccentric and the mechanism associated therewith from further movement. When, however, the electromagnet 126 is energized the armature or core 128 is 55 moved to retracted position and the end of the slide bar 130 is pulled out from under the nose of the latch 118. The latch spring 124 then becomes operative to swing the latch into engagement with the ratchet to cause the latch to be 60 engaged by a ratchet tooth and carried around therewith. The electromagnet is intended to be but momentarily energized so that the slide bar is positioned in the path of rotation of the latch before the latch has made a complete revolution. 65

Hence the slide bar is in position to be engaged by the latch and to cam it out of engagement with the ratchet upon the completion of a single revolution, thereby to stop further reciprocation of the mechanism. The bar also holds the 70 mechanism stationary with the eccentric at the top of its stroke.

In accordance with this invention a single punch device 114 is employed. Said punch device is carried by a system of copying linkages 75.

and particularly a pantograph system of pivotally connected links comprising the long punch carrying link 176, and the shorter link 178. Said links are maintained in parallel relation by a pair 5 of long and short cross links 180 and 182, respectively, which are pivoted to the links 176 and 178. The inner end of the link 178 is secured to a flange 184 located in a recess of the table 30 and formed on the upper end of a relatively long 10 stud shaft 186 journalled in a bearing block 188 secured to the underside of the table, see especially Fig. 6. This arrangement provides a steady pivotal support for the pantograph. The free end of the lever 180 is terminated in a pointer 190 hereinafter to be more fully described. The pointer, punch and axis of the pantograph linkage are in the same line and consequently the punch is caused to faithfully follow the movements of the pointer.

20 The rear part of the punch carrying arm 176 is bifurcated, the furcations 176a and 176b being on opposite sides of the stencil track 44. The furcation 176b at its rear end where it underlies the stencils in the track has a generally cylindrical 25 punch passage 192. The upper furcation 176a carries at its rear end the major part of the punch device 174. The punch device 174 comprises a barrel 194 which is fixed in and upstands above the rear end of said furcation 176a and 30 carries a cylindrical punch rod 196 the lower end of which is capable of being projected below the furcation 176a and through a stencil thereunder and into the passage 192 of the underlying furcation 176b. The punch rod 196 is urged continually upwardly by a helical spring 198 that encircles the rod within the barrel and bears against a shoulder 200 of the rod. The rod projects upwardly above the top of the barrel in a position to be engaged by the reciprocating plate 72 and moved downwardly through 40 the stencil.

It will be apparent that by moving the pointer 190 of the pantograph linkage the punch will be correspondingly moved and thus can be positioned into register with any selected perforation receiving zone 22 of the stencil to form a 45 perforation therein.

The pointer 190 is movable over an index plate 202 carried by a shelf 232 of the table 30. Said 50 index plate is divided into perforation indicating zones 204, there being as many such zones as there are corresponding zones 22 of the stencil and the relative disposition of such zones corresponding to the zones of the stencil. The index 55 plate zones are consecutively numbered as at 206, corresponding to the numbering 24 of the zones of the stencil except that the numbers are oppositely arranged. That is to say, while number one zone, for instance, of the stencil, occupies the uppermost left hand corner thereof, number one zone of the index plate, occupies the right hand corner. By positioning the pointer 190 of the pantograph system in register with any selected zone of the index plate, the punch 60 174 will be caused to be positioned in register with the corresponding zone of the stencil.

Each zone 204 of the index plate is provided 70 with a recess 208 preferably of conical or tapered configuration for accurately locating the pointer in engagement with the plate in a position corresponding to the perforation position in the corresponding zone of the stencil and holding the pointer and consequently the punch device against accidental displacement during the punching operation.

The pointer 190, see especially Fig. 5, comprises a bushing 210 secured in and upstanding above the free end of the link 180. A plunger 212 is reciprocable within said bushing and has a conical or tapered lower end 214 adapted to be depressed into seating engagement with any recess 208 of the index plate. Said plunger has an enlarged head or flange 216 at its upper end which is located movably within a cap 218. A heavy helical spring 220 is located within the cap between the upper end thereof and the head 216 and a lighter helical spring 222 is located under said head 216 and on the end of the bushing 210. The cap is provided with a vertically elongated slot 224 within which a screw 226, screw-threaded 15 into the bushing, is located whereby to limit the vertical displacement of the cap. The spring 222 normally holds the plunger 212 and the end cap in the uppermost positions thereof with the bottom wall of the slot 224 against the limit 20 screw 226. By pressing the cap 218 downwardly the light spring 222 yields causing the end of the plunger 214 to enter and seat in a depression 208 of the index plate in register with the plunger.

The cap 218 carries an axially located circuit 25 controlling contact pin 228 which is axially movable within the plunger 212 and normally is held by the spring 220 with its lower end withdrawn within the lower end of the plunger. When, however, the lower end of the plunger is seated in a 30 recess 208 further depression of the cap 218 causes the flexing of the spring 220 and thereby permits the movement of the pin downwardly beyond the end of the plunger and into the bottom of the recess 208 and into engagement with 35 the metallic contact plate 230 which underlies the index plate and is accessible through all of the recesses 208 therein. Said plate 230 is suitably insulated from the frame of the machine as by the shelf 232, which is of insulating material. 40 Said plate 230 is connected in series with the terminal of the solenoid 126 and a suitable power source 230a by a conductor 230b. The other terminal of the solenoid is grounded to the machine frame by a conductor 230c. Thus the energizing circuit for the solenoid is completed by 45 engagement of the pin 228 with said plate 230, thereby to effect a punching operation, said pin being mechanically and electrically connected to the machine frame through the links 180 and 178. 50

The operation of the machine is simple. The operative momentarily depresses the pedal 40 to effect the movement of a stencil into perforating position under the plate 72 and pointer 190 is then moved into position above a selected recess 55 208 of the index plate and the plunger 212 is positioned therein. The punch is thereby positioned in register with the corresponding perforation receiving zone of the stencil and at the same time is held against accidental sidewise displacement. The cap 218 is then further depressed momentarily to bring the pin 228 into engagement with the plate 230, thereby to effect energization of the solenoid 126 and a single punching operation of the plate 72. The pointer is then moved into a different position on the index plate and the operation is repeated until the desired 60 perforations have been placed on the stencil. After all desired perforations have been formed in the stencil the pedal 40 is then again momentarily depressed and the perforated stencil is moved out of perforating position and a new stencil is positioned therein.

I claim:

1. A card perforating machine adapted to form 75

- perforations in differently positioned perforation receiving zones, selected at will, of a stationary card, comprising a shiftable punch device positionable in register with the zones of said card selected at will, and a reciprocable punch operating member reciprocable into and out of operative relation with said punch device in any selected position thereof for effecting the operation thereof, said punch operating member being stationarily located with respect to the zone-selecting movements of said punch device, and said punch device being movable into any selected zone relatively to said punch operating member.
2. A card perforating machine adapted to form perforations in differently positioned perforation receiving zones, selected at will, of a card, comprising a reciprocable punch operating plate overlying the card, and a punch device located between said plate and card and characterized by being freely movable under said plate and over said card into register with the zones of said card selected at will, and means for effecting reciprocation of said plate into and out of operative relation with said punch device.
3. A card perforating machine adapted to form perforations in differently positioned perforation receiving zones, selected at will, of a stationary card, comprising a shiftable punch device movable into register with the zones of the card selected at will, a stationarily-located reciprocating member movable into operative relation with said punch device for operating it to perforate the card in any selected position of the device, and means for effecting reciprocation of said member, said punch device being movable into any selected zone relatively to said reciprocating member.
4. A card perforating machine adapted to form perforations in differently positioned perforation receiving zones, selected at will, of a card, comprising a punch device movable into register with the zones of the card selected at will, a reciprocating member engageable with said punch device for operating it in any position thereof, and means for positioning said punch device comprising an index plate having perforation indicating zones corresponding to the zones of the card, a pointer movable over said plate into register with the zones thereof selected at will, and copying mechanism interconnecting said pointer and punch device for positioning said punch device in register with a zone of the card corresponding with the zone of said index plate in register with said pointer by movement relatively to said reciprocating member.
5. A card perforating machine adapted to form perforations in differently positioned perforation receiving zones, selected at will, of a card, comprising a punch device movable into register with the zones of the card selected at will, a reciprocating member engageable with said punch device for operating it in any position thereof, and means for positioning said punch device comprising an index plate having perforation indicating zones corresponding to the zones of the card, a pointer movable over said plate into register with the zones thereof selected at will, and copying mechanism interconnecting said pointer and punch device for positioning said punch device in register with a zone of the card corresponding with the zone of said index plate in register with said pointer, said copying mechanism comprising a pantograph linkage having a link which carries said punch and another link which carries said pointer.

6. A card perforating machine comprising an index plate having a series of differently positioned perforation indicating zones, a copying linkage connected with said pointer, a punch device associated with said linkage and movable thereby into positions corresponding with positions of said pointer, means for supporting a card in operative relation with said punch device in any selected position thereof, and means independent of said linkage for operating said punch device in any selected position thereof.

7. A card perforating machine comprising card supporting means, a punch device having cooperating parts located on opposite sides of said supporting means, said punch device being movable into register with selected parts of a card in said supporting means, means for selectively positioning said punch device in register with selected parts of the card comprising an index plate having a plurality of perforation indicating zones, a pointer movable over said plate into register with selected zones thereof, copying mechanism connecting said pointer and punch device, and electro-means for operating said punch device in any selected position thereof.

8. A card perforating machine comprising card supporting means, a bifurcated link having its furcations disposed on opposite sides of said card supporting means, a punch device having parts carried by both of said furcations, a pointer operatively connected with said link for moving said punch device into register with selected parts of the card, an index plate cooperating with said pointer and having means thereon defining perforation indicating zones of the card, and means independent of said link for operating said punch device in the various selected positions thereof.

9. A card perforating machine comprising an index plate having differently positioned perforation indicating zones, a copying linkage including a link having a pointer movable over said index plate into register with selected zones thereof, said linkage also including a bifurcated link, a punch device having cooperating parts carried by the furcations of said link, a card guide way located between said furcations, and a stationarily-located reciprocating punch operating member engageable with said punch device in different selected positions thereof.

10. A card perforating machine comprising a card guide way, a reciprocating punch operating plate disposed in said guide way and reciprocable toward and away therefrom, a link, a punch device carried by said link under said plate and movable with said link into various positions under and in operative position with respect to said plate, means for effecting reciprocatory movement of said plate into and out of operative relation with said punch device to effect the perforating of a card in said guide way, an index plate having a plurality of perforation indicating zones, a pointer movable over said plate into register with said zones selected at will, and means connecting said pointer and link for effecting the positioning of said punch device in correspondence with the positioning of said pointer with respect to said index plate.

11. A card perforating machine comprising card holding means, a punch device movable over a card in said means, power mechanism for operating said punch device in any selected position thereof, and copy mechanism carrying said punch device and including an index plate for setting said punch device in different predetermined posi-

tions selected at will and effecting the operation of said punch operating mechanism.

12. A card perforating machine comprising a card holder, a punch device movable over a card in said holder, manually operated copy mechanism for shifting the position of said punch device and for locating said punch device in different positions selected at will, power means for operating said punch device in any position thereof, and means controlled by said manually operated means for effecting the operation of said power means. 5

13. A card perforating machine comprising a card holder, a punch device movable into different positions with respect to a card in said holder, means including a pointer for moving said punch device into various selected positions, power means for operating said punch device in any position thereof, and means controlled by said pointer for activating said power means to effect a punching operation of said punching device. 10

14. A card perforating machine comprising a card holder, a punch device movable into different positions with respect to a card in said holder, means including a pointer for moving said punch device into various selected positions, power operating mechanism for said punch device, and means operated by said pointer for effecting the operation of said mechanism. 15

15. A card perforating machine comprising a card holder, a punch device movable into different positions with respect to a card in said holder, copy mechanism carrying said punch device and including a pointer for moving said punch device into various selected positions, operating mechanism for said punch device in any selected position thereof, electromagnetic means controlling the operation of said mechanism and including controlling means for said electromagnetic means operated by said pointer. 20

16. A card perforating machine comprising a card holder, a punch device movable into different positions with respect to a card in said holder, copy mechanism carrying said punch device and including a pointer for moving said punch device into various selected positions, operating mechanism for said punch device in any selected position thereof, electromagnetic means controlling the operation of said mechanism and including controlling means for said electromagnetic means carried by said pointer. 25

17. A card perforating machine comprising a card holder, a punch device movable into different positions with respect to a card in said holder, means for selectively positioning said punch device with respect to the card including a pointer, and an index plate cooperating with said pointer and having a plurality of pointer engaging means operative to hold said pointer and said punch device in a selected set position, said pointer and index plate comprising cooperating contact members, and punch device operating mechanism controlled by said contact members. 30

18. A card perforating machine comprising a card holder, a punch device movable into different positions with respect to a card in said holder, means for selectively positioning said punch device with respect to the card including a pointer, and an index plate cooperating with said pointer and having a plurality of pointer engaging means operative to hold said pointer and said punch device in a selected set position, said pointer engageable means comprising recesses in said plate, said pointer having a part 35

movable into holding engagement with said recesses.

19. A card perforating machine comprising a card holder, a punch device movable over a card in said holder, means for setting said punch device in any selected position including an index plate having a plurality of differently positioned pointer holding means, and a pointer operatively connected with said punch device having a part movable into releasable engagement with a selected pointer engageable means. 5

20. A card perforating machine comprising a card holder, a punch device movable over a card in said holder, means for selectively positioning said punch device with respect to the card comprising an index plate having a plurality of differently positioned recesses therein, a pointer having an operative connection with said punch device, and a plunger movable into selected recesses. 10

21. A card perforating machine comprising a card holder, a punch device movable over a card in said holder, means for selectively positioning said punch device with respect to the card including an index plate having a plurality of differently positioned recesses, a pointer having an operative connection with said punch device and a part depressible into said recesses, and means responsive to the depression of said depressible part for effecting the operation of said punch device. 20

22. A card perforating machine comprising a card holder, a punch device movable over a card in said holder, means for selectively positioning said punch device with respect to the card including an index plate having a plurality of differently positioned recesses, a pointer having an operative connection with said punch device and a part depressible into said recesses, and circuit controlling means responsive to the depression of said depressible part for effecting the 30 operation of said punch device. 35

23. A card perforating machine comprising a card holder, a punch device movable over a card in said holder, means for selectively positioning said punch device with respect to the card, comprising a perforated index plate, a contact plate underlying the perforations of said index plate, a pointer having an operative connection with said punch device and movable over said plate into register with selected perforations thereof, said pointer having a part movable into a perforation and into electrical engagement with said contact plate, and means responsive to the electrical engagement between said movable part of said plate for effecting a perforating operation of 50 said punch device. 55

24. A card perforating machine comprising a card holder, a punch device movable over a card in said holder, mechanism for operating said punch device in any position thereof, electromagnetic control means for said punch operating mechanism, and means for selectively positioning said punch device with respect to a card including a perforated index plate, a contact plate underlying the perforations of said index plate, a pointer having an operative connection with said punch device and movable into register with the perforations of said index plate selected at will, said pointer and said index plate constituting the terminals of an excitation circuit for said electromagnetic means, and said pointer having a part movable into a selected perforation of said plate and into circuit closing engagement with said contact plate whereby to effect the operation of said punch operating mechanism. 60

25. A card perforating machine comprising a pointer, copying mechanism connecting said pointer and punch device, whereby said punch device is caused to be positioned in accordance with the position of said pointer, an index plate over which said pointer is movable, said index plate having a plurality of depressions corresponding to predetermined positions of said punch device, said pointer having a resiliently supported plunger arranged to be removably positioned within a selected depression whereby to hold said pointer and punch device against unintended movement, and a contact plate underlying said depressions and accessible therethrough, said pointer having a contact pin movable into engagement with the contact plate, said contact plate and pin constituting the terminal of an excitation circuit for said electromagnetic means. 5
- 10 26. A card perforating machine comprising a card holder, a punch device movable over a card in said holder, means for operating said punch device in any position thereof, electromagnetic control means for said operating means, a 10
